ATTORNEY

UNITED STATES PATENT OFFICE.

WILLIAM J. BROOME, OF LOS ANGELES, CALIFORNIA, ASSIGNOR TO KUNKEL STAMPING & MANUFACTURING CO., A CORPORATION OF CALIFORNIA.

FOLDING BED.

Application filed January 27, 1925. Serial No. 5,123.

This invention relates to beds, and especially to foldable or collapsible beds and camp beds.

An object of this invention is to provide a collapsible metal structure bed which, while it may be very compactly folded into a small space, can be easily unfolded, extended and set up in a very short period of time. An object is to provide a knock-down bed incorporating a means whereby a mattress spring fabric may be highly tensioned between end bars of the bed frame so that the spring will be capable of comfortably supporting two or more persons, and yet enabling the tensioning to be performed by a woman or child of average strength.

An object is to provide a camp bed which, while having elements of low cost of manufacture and of simple form, provides for durability, strength and safety.

An object is to provide a foldable camp bed of obvious mechanical manipulation enabling anyone of ordinary ability to unpack, extend and fully set up the bed with ease.

Another object is to provide a novel and substantial foldable and locking brace for relatively foldable elements.

Other objects and advantages will be made manifest in the following specification of apparatus embodying one form of the invention illustrated in the accompanying drawing; it being understood that modifications, variations and adaptations may be resorted to within the spirit of the invention and the scope thereof as here claimed.

Figure 1 is a perspective showing the bed in nearly erected position of the parts.

Figure 2 is a perspective showing the initial setting up steps.

Figure 3 is a detail showing a locked bed leg.

Figure 4 is a cross-section showing the brace latch.

Figure 5 is a longitudinal section of connected ends of an extended rail.

Figure 6 is a sectional detail showing the locked tension brace.

Figure 7 is an end view of a collapsed and packed bed; a receptacle being shown in dotted lines. Figure 8 is a perspective of the set up bed; the fabric being broken away. Figure 9 is a side elevation of an extended rail.

An object of the invention is to provide

as few fully detached elements as practical in the provision of a substantial and readily adjustable bed.

As shown, the bed includes a pair of duplicate side rails each having a pair of channel-iron sections 2-3, which are internestable, as shown in Fig. 7, in a collapsed position, and are pivotally attached on a pivot 4 to unfold in alignment. The section 2 has but a single hole for the pivot pin 4, but section 3 has a plurality of pin holes 5 so that the effective length of the extended rail may be varied for a purpose later mentioned.

Also mounted upon pivot 4 of a rail is an elongated hook-link 6. A tensioning brace including a member 7 is also mounted on pivot pin 4. This brace has an intermediate lever arm 8 pivoted at 9 on the swinging end of member 7 and the projecting short arm 8^a of the lever 8 is attached at 10 to the rear end of a hook 11. The lever 8, when swung away from the link 7, pulls in the hook 11 and the composite brace 7-8-11 can then be dropped into the rail section 3. The hook-link 6 can also be folded down 80 into the section 3, and then the section 2 can be folded into the section 3, as in Fig. 7.

Sections 2 of the rails have hook slots 2^a and sections 3 have straight slots 3^a, in the ends. Each rail forms a complete, interchangeable unit.

Another unit consists of a bed spring fabric having attached end stiles with permanently attached, foldable legs. The end stiles each include a stout piece of angle-iron 15 along one flange of which are attached springs 16; the springs of one stile being connected to those of the other by a suitable pliant mattress support S. This is preferably a wire fabrication capable of being compactly folded without any possibility of becoming tangled, and being readily unfoldable when one stile is pulled up from the folded support resting upon the floor or ground preparatory to setting up the bed, 100 as in Fig. 2.

Along the inner face of the other flange of the stile 15 are provided pivots 17 carrying the upper ends of stout legs 18, capable of being folded into alignment along the stile. A spacer 19 holds the leg 18 slightly from the flange of the stile and in the plane of the spacer is a floating link 20 slotted at 21 to receive a fixed pin 22. The swinging end of link 20 is attached to a link 23 which 110

is connected to a pivot 24 in a leg 18. A pivot pin 25 connecting links 20-23, extends at 25^a to form a strong bolt or latch to snap into a hole 26 provided in the stile flange. The purpose of the slot 21 is to allow the bolt to be shifted until it finds its way into the bolt hole 26, thus facilitating locking up the leg as in Fig. 3. This form of locking brace is highly efficient and safe.

10 It cannot unfold beyond the limit of the aligned links 20-23 and if the bolt-pin 25 is not set in its hole 26, the link 23 will swing up against the top flange of the stile and so hold the leg from inward collapse.

15 Fig. 7 clearly shows the intermediate and internested rail members and their enclosed hook-links and tension braces, the stacked folds of the support S, and the end stiles 15 as lying in a carton C, shown in dotted lines. To set up the bed it is taken from the carton and the rails are lifted from the stack of web folds F. Then the legs 18 of the upper stile are unfolded and locked and stood upright while the hook-slot end of one 25 of the rails is slipped into a leg; these being here shown as of channel-iron, and hooked down over a fixed bar 27 in the leg. Preferably the rail sections are unfolded before they are hooked to the first set up legs. The 30 second rail is then in a similar manner hooked to the other leg. The hook links 6 are passed down over lower bars 29 in the legs and the far ends of the rails are rested on the floor or ground while the 35 remaining, free stile is pulled up over the set up end of the bed. The second stile is shifted along the rails to the far end and then its legs 18 are unfolded and locked by bolt 25. One leg is now hooked by bar 28 in slot 3^a in the near rail end; the fabric being slack. The first hook-link 11 is now extended by hand-lever 8 to pass over a lower bar 29, and the leg is now pulled in at the bottom and thrown out at its top, thus placing its side of the fabric S under tension, as in Fig. 1. The pulling in of the bottom of the leg is accomplished by pulling hand-lever 8 around over the hook-link 11, effecting a shortening of the tension device 7-8-11.

40 This leaves the other side of the fabric slack as is indicated by dotted line L. The second tension device is now extended by its handle 8 until its hook 11 engages the lower bar 29 in the near leg; the slotted rail end 45 being hung on the upper bar 28 in the leg. The hand-lever 8 is then thrown around over its hook 11 with a firm pressure which draws in the last leg 18 and straightens it up to strongly tension the fabric S.

50 By actual demonstration, the tensioned fabric is found to support three adults of average size without undue sagging.

55 Any desired means may be employed to secure the tension-brace parts 8-11 in contracted position. This means may include a

simple L- or T-head pin or screw 31 on one of the parts to pass through a slot in the other part and then be turned across the slot and be held in interlocking position.

To shorten or lengthen the rails, the pins 4 are placed in the desired holes 5 of the series in the rail sections 3.

An important feature of the invention is that the bed can be lengthened by shifting the sections 3 and their braces 8-11 by 75 simply inserting the pins 4 in the desired holes 5 of the sections 3. When the braces 8-11 are clamped to tighten up the fabric S the legs 15 are always brought perpendicular to rail sections 3. The springs 16 allow for 80 shortening or lengthening of the rails without tilting of the legs on the ends of the sections 3. Lengthening the rails, increases spring tension but does not change the angle 85 of the legs.

What is claimed is:

1. A collapsible bed including a pair of foldable side rails, rigid end stiles having pivoted legs, a mattress support connecting the stiles, means for detachably connecting the legs to the ends of the rails, rigid, contractable and extensible support tensioning means including levers connected to the lower ends of the legs and to the rails. 90

2. A collapsible bed including foldable side rails, legs detachably connected to the ends of the rails, end stiles connected to a mattress support and being pivotally attached to the legs, and extensible and contractable braces pivotally connected to the rails and attachable to the lower ends of the legs and having bar-like link parts lockable in alignment. 95

3. In a collapsible bed, a set of legs, end stiles having a pliable mattress support connecting them, side rails mounted on the legs, a link pivotally attached to a rail, a hook to engage a leg, and an intermediate lever having a short arm connecting the near ends of the hook and link whereby to form a 105 rigid bar-like brace between leg and rail. 110

4. In a collapsible bed; end stiles to which a mattress support is attached and legs for the stiles, rails connecting the legs in side pairs and being attached thereto below the level of the end stiles, and means for tensioning the mattress support and bracing coordinate legs including a member attached to a leg, a coordinate member attached to the relative rail, and a lever having a short arm connecting the near ends of said members to effectually lengthen or shorten said means by pulling together or separating said members by endwise movement of them relatively, and a locking means for the extended 115 brace means. 120

5. In a folding camp bed, a pair of sectional side rails, end stiles connected by a mattress support, folding legs attached to the end stiles, means connecting the outer 130

ends of the rail sections to the legs at points below the level of the stiles, rigid braces connecting the intermediate ends of one set of rail sections and their legs, and rigid braces

5 connecting the other set of rail sections to their respective legs and being effectively variable in length to tighten the said support.

6. In a folding camp bed, a pair of side 10 rails each including pivotally connected sections, end stiles connected by a pliable mattress support, folding legs attached to the stiles and connected to the outer ends of the rails, and brace means mounted on the pivots 15 of the rails and being connectable to the legs.

7. In a folding camp bed, a pair of side rails each including pivotally connected sections, end stiles connected by a pliable mat-

tress support, legs for supporting the stiles 20 and rails, and means for bracing the legs to the rails and including elements mounted on the pivots of the rails, members attachable to the lower portions of the legs, and an intermediate lengthening and shortening 25 connection between said elements and said members.

8. In a folding camp bed, a pair of side rails each including pivotally connected sections of channel iron, bracing means mounted on the pivots of the sections and being foldable into the channels of the sections, end stiles having a connecting, pliable mattress support, and legs for supporting the stiles and the rails and to which the unfolded, outer ends of the brace means are attachable to brace the set up bed.

WILLIAM J. BROOME.
